SHAFT MILLING AND GRINDING MACHINE

Owen D. Premo, Muskegon Heights, Mich.

Application November 13, 1940, Serial No. 365,535

2 Claims. (Cl. 90—11)

This invention relates to shaft milling and grinding machines, the primary object of the invention being to provide a machine of this character which may be used as an attachment for lathes, traveling head planers, draw-cut shapers having internal arbors, boring mills or the like.

An important object of the invention is to provide a machine of this character wherein the milling or grinding heads thereof may be readily adjusted with respect to each other, adapting the heads for use in accurately milling or grinding various types of curved surfaces.

Another important object of the invention is to provide a machine of this character including a special arrangement of gearing which will cause the cutter to rotate in a direction to equalize the cutting forces.

Still another object of the invention is to provide a machine which may be used in accurately forming molding from metal or wooden bar stock.

With the foregoing and other objects in view, which will appear as the description proceeds, the invention resides in the combination and arrangement of parts and in the details of construction hereinafter described and claimed, it being understood that changes in the precise embodiment of the invention herein described, may be made within the scope of what is claimed, without departing from the spirit of the invention.

Referring to the drawings:

Figure 1 is a plan view of a machine constructed in accordance with the invention.

Figure 2 is a side elevational view thereof.

Figure 3 is a longitudinal sectional view through the machine.

Figure 4 is a modified form of the invention illustrating the principles of the invention as carried out in a pencil sharpening device.

Figure 5 is a sectional view taken on line 5—5 of Figure 4.

Referring to the drawings in detail, the base of the machine is indicated by the reference character 5, the base being supported by bolting the base to the lathe, traveling head or machine with which the attachment is used, as by means of bolts 6.

The body portion of the machine comprises substantially circular members 7 which are hollow and have their open sides disposed outwardly, as clearly shown by Figure 1 of the drawings. Openings 8 are formed in the members 7, and provide clearances so that material such as chips, grindings or the like removed from the bar un-

der treatment, may pass from the circular members 7. Tubular shafts 9 operate in openings formed at the inner ends of the circular members 7, the tubular shafts 9 providing bearings for the bar under treatment, which in the present showing is indicated at A. Keyed to the tubular shafts 9 are plates 10 which are disk-like in formation, the plates being bolted to the gear 11 as by means of bolts 12 which pass through the plates 10 and gear. The gear 11 is formed with a central opening, so that the bar may be passed through the machine and through the gear. The circular members 7 are formed with recessed portions in which the ring gears 13 are mounted. Keyed to the outer ends of the tubular shafts 9 are arms 14 which have openings formed adjacent to the outer ends thereof, which openings receive the tubular bearings 15 to which the cutters 16 are secured, the cutters 16 having openings to receive the inner ends of the tubular bearings, where the tubular bearings are secured to the cutters, by means of the screws 17. Extending into the tubular bearings 15 are shafts 18 that have reduced ends on which the gears 19 are mounted, the gears 19 meshing with the ring gears 13. The gears 19 are secured to the shafts 18 to rotate therewith.

As shown, the inner ends of the shafts 18 are tubular and are formed with slots extending inwardly from the inner ends thereof, the slots accommodating the pins 20 carried by the tubular bearings 15, so that the shafts 18 will rotate with the tubular bearings 15. Coiled springs 21 are disposed between the inner ends of the shafts 18 and inner ends of the tubular bearings 15, the coiled springs being normally under tension, to urge the cutters 16 towards their work, and to compensate for material removed from the work by the cutters.

The inner ends of the tubular shafts 9 are keyed to the plates 10, so that rotary movement of the gear 11, will produce a relative rotary movement of the tubular shafts 9 to rotate the arms 14. Power is applied to the gear 11, through the worm 22 mounted on one end of the power shaft 23, that in turn is rotated by the motor 24. Thus it will be seen that due to this construction, the bar or work under treatment, will be engaged by the cutters 16, operating at opposite sides of the work, and due to the rapid rotation of the cutters, the bar moving through the machine, will be ground or milled accurately and evenly.

The shafts 18, are disposed in openings formed in the hollow supports 25 that are provided with

bearings 26 extended into bearing openings formed in the covers 27 that are used to guard the cutters. These covers 27 are bolted to the circular members 7, by means of the bolts 28.

In the form of the invention as illustrated by Figure 4 of the drawings, the principle of the invention has been used in tapering the ends of bars or the like, and in the present showing, the cutters are used in a pencil sharpener. The reference character 29 designates the hollow base of the sharpener, in which the motor 30 is mounted. The body portion of the sharpener is indicated by the reference character 31 and as shown, is provided with a threaded annular flange 32 fitted within the upper end of the hollow base 29. The body portion 31 is formed with a central opening providing a bearing for the vertical shaft 33 that extends into the hollow base 29 to connect with the motor shaft. At the upper end of the shaft 33, are arms 34 that have openings disposed adjacent to the free ends thereof, for the reception of the hollow shafts 35, which shafts are identical in construction with the members 15. The cutters are indicated by the reference 36 and have their opposed inclined surfaces so arranged that they will engage opposite sides of the work to taper or sharpen the end thereof. Extending into the hollow shafts 35, are shafts 37 that extend through the movable casing 38 and are supplied with gears 39 at their outer ends, the gears 39 meshing with the ring gear 40 held stationary within the body portion 31.

Coiled springs 41 are mounted within the hollow shaft 35 and bear against the shaft 37, normally urging the cutters 36 towards each other, to insure the cutting faces thereof being held to their work to compensate for material removed from the work. It will be seen that as the shaft 33 is rotated, the member 38 together with the shafts 37 will be rotated in horizontal planes. As the members 38 rotate, the gears 39 will rotate by reason of their contact with the ring gear 40. This rotary movement of the gears 39

will cause the cutters 36 to rotate, to accomplish the tapering result.

What is claimed is:

1. A shaft milling machine comprising a base, 5 a body portion mounted on the base and comprising hollow members, aligned hollow shafts extending into the hollow members, pairs of arms having bearings, secured to the inner ends of said hollow shafts and operating within the 10 hollow members, a gear secured to the adjacent ends of the hollow shafts between the hollow members, ring gears secured within the hollow members, shafts mounted in the bearings of the pairs of arms, pinions on the outer ends of the 15 latter shafts, said pinions being in mesh with the ring gears, milling tools mounted on the inner ends of the latter shafts, said milling tools adapted to be rotated through the ring gears and pinions, when the pairs of arms are rotated, and said body portion having openings aligning 20 with the hollow shafts, and through which a shaft to be milled is extended.

2. A shaft milling machine, comprising a hollow 25 stationary body portion, a ring gear within the body portion, a hollow rotary tool support mounted within the stationary body portion, tubular shafts extending into the body portion, arms secured to the hollow shafts, said arms extending into the tool support, said arms having bearings at their free ends, hollow tool shafts 30 extending through the bearings, grinding tools on the inner ends of the tool shafts, shafts extending into the tool shafts, the pinions on the latter shafts meshing with the ring gears, coiled 35 springs mounted within the hollow tool shafts and bearing against the inner ends of the shafts extending into the tool shafts, and adapted to normally urge the tools inwardly towards the shaft being milled, said hollow body portion having openings in the ends thereof through which a shaft to be milled is moved, and means for rotating said tools around the shaft being milled.

OWEN D. PREMO.
